UNITED STATES PATENT OFFICE.

DANIEL LAWSON, OF NEW YORK, N. Y.

EXTENSIBLE HANDLE.

No. 808,992.

Specification of Letters Patent.

Patented Jan. 2, 1906.

Application filed April 6, 1905. Serial No. 254,248.

To all whom it may concern:

Be it known that I, DANIEL LAWSON, a citizen of the United States, and a resident of the city of New York, borough of the Bronx, 5 in the county and State of New York, have invented a new and Improved Extensible Handle, of which the following is a full, clear, and exact description.

My invention relates to extensible handles—such, for instance, as are used upon shovels and analogous implements for handling coal, and also admitting of general use in instances where longitudinal cylindrical handles are employed.

Reference is to be had to the accompanying drawings, forming a part of this specification, in which similar characters of reference indicate corresponding parts in all the figures.

Figure 1 is an elevation, partly in section, showing my improved handle as applied to a coal-shovel. Fig. 2 is an enlarged cross-section upon the line 2 2 of Fig. 1 looking in the direction of the arrow and showing the positions of the several parts when the telescopic members are locked rigid relatively to each other; and Fig. 3 is a view similar to Fig. 2, with the exception that the telescopic portions are shown as unlocked, so that the 30 length of the handle may be changed.

The bowl of the shovel is shown at 4 and is provided with a cylindrical portion 5, extending therefrom, this portion being secured by means of rivets 6 upon a tubular member 7, made, preferably, of steel and provided at its upper end with an annular portion 8, which is comparatively thick. A tube 9 is provided with an annular head 10, also comparatively thick, and with a pair of 40 oppositely-disposed slots 11. Encircling the tube 9 and partially encircling the tubular member 7 is a third tube 12, provided at its lower end with a comparatively thick annular portion 13. The hand-grip 14 is mounted within the fork 15, which terminates in a neck 16, as indicated in the upper portion of Fig. 1. A cylindrical rod 17, preferably of steel, is provided at its lower end with oppositely-disposed cam-lobes 18 and is revolvably 50 mounted within the neck 16. The upper end of this rod is provided with a crank portion 19, having a thumb-piece 20 integral therewith and adapted to move into the position indicated by dotted lines in Fig. 1. A 55 screw 20^a passes through the wall of the tube

12 and the thick annular head 10 of the tube 9, so as to penetrate the stem 16, as indicated in Fig. 1. The tube 9 at its lower end and upon opposite sides of the head 10 is provided with thickened portions 9^a, which 60 serve as cam-lobes, as will be understood from Figs. 2 and 3. An annular bead 18^a is carried by the rod 17 and integral therewith. This rod 17 is, in effect, a rocking stem actuated by means of the crank portion 19 and 65 the thumb-piece 20. The inner and outer tubes 9 and 12 and the intermediate tube 7, together with their accompanying parts, constitute the handle.

The operation of my device is as follows: 70 When the operator desires to render the handle comparatively short, he turns the crank portion 19 into the position indicated by dotted lines in Fig. 1, or, in other words, gives it a quarter-turn, and then pushes upon the 75 hand-grip 14, so as to drive the annular portion 8 of the tube 7 to a point adjacent to the annular head 10, preferably resting against the same. He then restores the crank portion 19 to the position indicated by full lines 80 in Fig. 1. The movement of the crank portion 19 into the position indicated by dotted lines causes the cam-lobes 18, carried by the rocking stem 17, to relax their grip against the cam-lobes 9^a, as will be understood from 85 Fig. 3. When, therefore, the crank portion 19 is restored to its position, (indicated by full lines in Fig. 1,) the cam-lobes 18 of the stem 17 are forced into firm engagement with the cam-lobes 9^a of the tube 9 and cause the 90 lower end of this tube to swell and rigidly lock against the inner surface of the tube 7. This renders the handle rigid. To lengthen or shorten the handle to any desired extent, the crank portion 19 is moved, as above, into 95 the position indicated by dotted lines in Fig. 1, the tube 7 being drawn out or in to the desired extent, and the crank portion 19 again restored to its position. (Indicated by full lines.) 100

It will be noted that the annular portion 13 of the tube 12 is at all times in the same plane as the cam-lobes 18 and 9^a, so that the strain due to the gripping action of the cams is taken up by the annular portion 13, which 105 is to all intents and purposes a steel band possessing great strength.

The operator can, if he so desires, change the length of the handle at comparatively short intervals and can maintain the upper 110

2
end of the tube 7 comparatively cool by so doing—that is to say, each time the handle is extended a comparatively cool portion of the tube 7 is presented below the annular portion 13, and this cool portion may be grasped by the operator without danger of burning his hands. In other words, the upper end of the tube 7 may be momentarily protected by the outer tube 12 if the operator uses the shovel for a few moments in such relation as would ordinarily cause the heating of the tube 7 if fully extended.

15 The telescopic action of the handle is accomplished without materially weakening the handle, for the reason that the construction above described possesses adequate strength for all ordinary purposes.

Having thus described my invention, I claim as new and desire to secure by Letters

20 Patent—

1. The combination of a fork, a hand-grip mounted therein, an inner tube provided with an annular portion encircling a portion of said fork, an outer tube encircling said inner tube and spaced therefrom by said annular portion, a telescopic member disposed intermediate of said inner and outer tubes and free to slide relatively thereto, and means for locking said telescopic member rigidly in relation to said inner and outer tubes.

2. The combination of a fork, telescopic members connected therewith, one of said telescopic members being provided with cam-lobes, a rocking stem mounted within said fork and provided with cam-lobes mating

35 said first-mentioned cam-lobes, and means

controllable by hand for causing said stem to rock.

3. The combination of telescopic tubular members adapted to slide relatively to each other, one of said members being provided with cam-lobes, a rocking stem disposed within said tubular members and provided with cam-lobes mating the cam-lobes first mentioned, means controllable at will for 45 turning said rocking stem so as to force all of the cam-lobes into locking engagement, and a member connected with one of said tubular members and provided with a hand-grip.

4. The combination of an inner tube 50 provided with a bowl or the like, an outer tube encircling said inner tube and slideable relatively thereto, said outer tube being provided with a handle portion, a revoluble member mounted centrally within said inner tube and adapted to be turned at will by hand and cam mechanism operated by said revoluble member for securing said inner and outer tube rigidly together.

5. The combination of an inner tube 60 provided with a bowl or the like, an outer tube partially encircling said inner tube and slideable relatively thereto; and means for temporarily securing said outer tube and said inner tube rigidly together.

In testimony whereof I have signed my name to this specification in the presence of two subscribing witnesses.

DANIEL LAWSON.
